(57) **CLAIM**

The ornamental design for a container waist, as shown and described.

DESCRIPTION

FIG. 1 is a front perspective view of a container having a container waist showing our new design;

FIG. 2 is a front elevational view of the container having the container waist shown in FIG. 1, the rear, left side and right side elevational views being identical;

FIG. 3 is a cross-sectional view of the container waist along line 3—3 of FIG. 2;

FIG. 4 is a cross-sectional view of the container waist along line 4—4 of FIG. 2; and,

FIG. 5 is a cross-sectional view of the container waist along line 5—5 of FIG. 2.

The broken lines are for environmental purposes only and form no part of the claimed design.
